UNITED STATES PATENT OFFICE.

JACOB P. BUSCHER, OF ROCK RAPIDS, IOWA.

PIN SPOTTER AND PIN.

Application filed September 21, 1927. Serial No. 220,913.

The object of my invention is to provide a pin spotter of the kind used for accurately centering pins on the spots of a bowling alley.

It is my purpose in this connection to provide a pin spotter of very simple, durable and relatively inexpensive construction.

Another purpose of the present invention is to provide such a pin spotter so constructed and arranged that the device may be readily adapted for use on bowling alleys already built and installed or may be installed in connection with the original manufacture and installation of the alleys.

Another purpose of the present invention is to provide a novel construction for mounting pins in an alley for cooperation with the pin spotter.

Still a further object is to provide the combination of a spotter with pins mounted in the floor but not directly fastened to the spotter mechanism.

Another object is to provide a bushing for receiving the movable pin, which bushing can be conveniently and easily installed in the alley floor.

With these and other objects in view, my invention consists in the construction, arrangement and combination of the various parts of my pin spotter and pin, whereby the objects contemplated are attained, as herein-after more fully set forth, pointed out in my claims, and illustrated in the accompanying drawings, in which:

Figure 1 is a plan view of one end of a bowling alley floor, the spotter being shown in dotted lines, for illustrating the general arrangement of the spotter with relation to the floor.

Figure 2 is a top or plan view of the pin spotter, parts being broken away and parts being shown in section.

Figure 3 is a vertical, detail, sectional view taken on the line 3—3 of Figure 1.

Figure 4 is a view similar to that of Figure 3, illustrating the spotter in a different position of its movement.

Figure 5 is a vertical, transverse, sectional view taken on the line 5—5 of Figure 4.

Figure 6 is a vertical, sectional view taken on the line 6—6 of Figure 4, illustrating the construction and arrangement of the spotter actuating means; and

Figure 7 is a detail, sectional view taken on the line 7—7 of Figure 1 and illustrating the cooperating parts for actuating a centering pin.

In the accompanying drawings, I have used the reference numeral 10 to indicate generally the floor of a bowling alley.

A space must be provided underneath the 60 alley floor 10 at the rear end of the alley where the pins are set up for receiving the spotter. Access may be had to this space from the alley pit. In this space underneath the floor is installed the spotter.

My improved spotter comprises a frame 65 adapted to be installed in fixed position underneath the rear part of the alley floor 10 and a cooperating movable frame seated or supported on the fixed frame and adapted 70 to actuate the centering pins.

Suitable means are carried by the fixed frame for actuating the movable frame. The actuating means are operated from the pin 75 setter, although my spotter may be otherwise actuated for instance by the foot of the pin setter boy.

For purposes of clearness, it may be said that it is quite a general practice in the installation of the bowling alleys to provide 80 mechanical pin setters. These are devices in which pins are placed and by which the pins are set upright and in approximately their proper positions on the alley floor.

The pin setters now on the market do not 85 set the pins with exact accuracy upon the proper spots on the floor. Therefore in many alleys a pin spotter is employed.

The pin spotter actuates pins projecting 90 through the floor of the alley into recesses in the bottoms of the ten pins for accurately centering the ten pins on the proper spots.

My present invention relates to pin spotters of the kind just mentioned.

It might be mentioned in this connection 95 that pin spotters may be employed without mechanical setters, in which case pin boys would set up the pins with approximate accuracy, and a spotter such as is the subject of my present application could be used for 100 completing the accurate spotting of the ten pins.

Where a pin setter of the kind above mentioned is employed, I preferably provide 105 means for actuating the spotter automatically from the setter.

Fixed frame.

I shall first describe the fixed frame forming a part of my improved pin spotter. My 110 fixed frame is illustrated in Figures 2, 3, 4 and 5. It is substantially triangular in out-

line, having a transverse, upwardly opening channel-shaped member 12 forming the base of the triangle.

Secured to the frame member 12 at its ends 5 are forwardly inclined horizontal side frame members 14, preferably made of angle bars with an upright flange 14^a and a horizontal, inwardly extending flange 14^b.

The forward ends of the side frame members 14 are connected by a transverse angle bar frame member 16, which has a lower, horizontal flange 16^a with an upwardly extending flange 16^b at its rear edge.

Between their ends, the flanges 14^b of the frame members 14 are connected by a transverse, connecting, upwardly opening channel-shaped frame member 18.

At their rear ends, the frame members 14 are connected by the upwardly opening, channel-shaped member 12 already mentioned.

The channel bar frame members 12 and 18 and the angle bar frame member 16 terminates short of the upwardly projecting flange 14^a, as illustrated for instance in Figures 2, 25 and 5.

The upwardly projecting flanges 14 and the ends of the frame members 12, 18 and 16 thereby form guides for the members of the movable frame hereinafter to be described.

30 The fixed frame just described is shored up or supported by timbers, plank or the like 20 until the fixed frame rests at the proper height under the floor 10.

The supporting members 20 are preferably arranged under the side frame members 14, so as to leave ample room underneath the fixed frame along its median, central line, for affording room for the operating mechanism hereinafter described.

40 For properly anchoring the fixed frame to the floor 10 for making certain that the fixed frame will always be properly placed with relation to the floor 10, I provide a pair of brackets 22 bolted or otherwise secured to the frame member 12 as at 22^a, and provided at their rear ends with upwardly projecting portions secured to the floor 10 as at 24. (Figures 2 and 3.)

I have described the fixed frame without 50 particular reference to the movable frame, but it should perhaps be understood that the movable frame is seated on the fixed frame before the fixed frame is installed in position under the floor.

55 *Movable frame.*

I will now describe the movable frame.

The movable frame is in the shape of a true triangle having the rear member 26 and the 60 side members 27, as shown in Figure 2, welded or otherwise secured together at their ends.

The frame members 26 and 27 are in the form of angle bars and the angle bar frame members 27 have their horizontal flanges up, 65 and their vertical flanges extending down-

wardly at the outer edges of the horizontal flanges, as clearly illustrated for instance in Figure 5.

The side members 27 of the movable frame are connected by a transverse, downwardly opening, connecting channel bar frame member 28, shown in Figures 2 and 3, and by a second shorter, similar, downwardly opening channel bar frame member 30, located forwardly with relation to the member 28.

The downwardly projecting flanges of the channel bar members 27, which for convenience are marked 27^a (Figure 5) rest in guides formed between the flanges 14^a of the members 14 and the ends of the frame members 12, 18 and 16.

The vertical movement of the movable frame is short enough so that when the pin spotter is installed, the flanges 27^a will always thus be properly guided.

Because of the triangular shape of the fixed and movable frame members, the movable frame can not travel forwardly or rearwardly with relation to the fixed frame and will always be accurately guided.

The movable frame will always drop by gravity to its position seated on the fixed frame.

For lifting the movable frame for actuating the centering pins, the following means 95 are provided.

Movable frame actuating means.

The transverse frame member 18, forming a part of the fixed frame, is provided on its under side at its middle with a pair of downwardly extending ears 32. Pivoted between the ears 32 by means of a pin 34 is a lever 36, which may have the form of a downwardly opening channel bar.

105 The lever 36 is the operating lever by which the movable frame is raised. The lever 36 is of such length that its forward end stands immediately below the center of the transverse frame member 30 of the movable frame. Between the forward end of the lever 36 and the cross member 30 of the movable frame a spacer or filler member 40 is secured to the under side of the member 30 for engagement by the lever 36, as best illustrated 110 in Figure 4.

The pivot pin 34 is readily detachable and may have the cotter pins 42 extended through its ends for preventing its accidental removal.

115 The lever 36 projects rearwardly beyond the fixed and movable frame members. Mounted on the upper side of the lever 36 near its rear end is a T-shaped actuating member 44 for operating the secondary levers hereinafter referred to.

The arms of the T-shaped member 44 project laterally beyond the lever 36, as shown for instance in Figure 5.

Pivotedly supported between their ends on the rear flange of the fixed frame member 130

12 on opposite sides of the middle thereof are the secondary actuating levers 46, which at their inner ends have projecting pins 48, which stand below the projecting arms of 5 the member 44, as shown in Figures 4 and 5.

The outer ends of the secondary levers 46 stand just beneath the rear ends of the side frame members 27 of the movable frame. (Figure 5).

10 The weight of the movable frame is such that it normally holds the lever 36 in nearly horizontal position as shown in Figure 3.

When the rear end of the lever 36 is depressed and that lever is moved from its position shown in Figure 3 to its position shown in Figures 4 and 5, it will be seen that this movement swings the forward end of the lever upwardly causing its forward end to engage the frame member 30 for raising the 20 forward end of the movable frame.

Simultaneously the downward movement of the rear end of the lever 36 and the member 44 moves the inner ends of the secondary levers 46 downwardly, thus simultaneously, 25 automatically raising the outer ends of the secondary levers 46 and raising the rear ends of the side members 27 of the movable frame.

The movable frame is thereby raised vertically and is maintained in horizontal position 30 during its rising movement.

When the downward pressure on the rear end of the lever 36 is removed, the weight of the movable frame (see Figure 4) will cause that frame to drop downwardly to its 35 position shown in Figure 3, and to automatically return the lever 36 from its position shown in Figure 4 to its position shown in Figure 3.

The actuation of the lever 36 may be caused 40 by the foot of the pin boy or otherwise.

Since it is my purpose to install my pin spotter at times in alleys where pin setters are used, I have also illustrated a mode of construction whereby the lowering of the pin 45 setter for setting up the ten pins on the alley floor will actuate the pin spotter for completing the accurate spotting of the ten pins.

Referring now to Figure 4, I have illustrated a portion of a pin setter having the 50 frame 50 with the rear transverse member 52. Bolted or otherwise secured to the member 52 is a bracket 56 having a projecting member 58, which is provided with a bore to receive a plunger actuating pin 60. The pin 55 60 may be adjustably mounted in the member 58 by means of a set screw 62.

The alley floor 10 or a special member 64 projecting rearwardly therefrom supports an upright bushing 66 having at its upper end 60 the flange 68 countersunk in the floor or in the member 64 and projecting downwardly and through or beyond the floor or the member 64, as shown in Figures 4 and 6, and having at its lower part the external screw 65 threads 70 to receive a nut 72.

A plunger 74 is slidably received in the lower part of the bushing 66 with its lower end resting upon the rear end of the lever 36.

The upper end of the passage 66^a through the bushing 66 is preferably flared as at 66^b 70 to insure the entrance of the plunger actuating pin 60 into the hole or bore 66^a.

It will be seen that when the movable frame is in its normal position, resting on the fixed frame, as shown in Figure 3, and the 75 lever 36 is consequently in its position with its rear end raised, the plunger 74 will be in raised position.

The parts are so constructed that the 80 plunger 74 never projects above the bushing 66.

When the pin setter is lowered to position for setting up the ten pins on the alley floor, the downward movement of the frame member 52 will carry with the pin setter the 85 plunger actuating pin 60, causing it to enter the bushing 66 and strike the top of the plunger 74 and force the plunger downwardly for depressing the rear end of the lever 36 and thus raising the movable frame. 90

When the pin setter is raised, the movable frame is permitted to drop by gravity, and the movement of the lever 36 will raise the plunger 74, which will offer practically no resistance to the lever movement. 95

I will now describe the centering pins of the kind preferably used with my spotter.

Centering pins and mountings.

One objectionable feature of some pin 100 spotters arises from the difficulty of replacing the centering pins in case any of them should be injured.

I have provided a centering pin bushing and a centering pin adapted to cooperate 105 therewith and coact with the spotter of such construction that either the bushing or the pin may be quickly and easily removed or installed.

It will be understood that the ten pins 76 110 now manufactured are provided with tapering recesses or countersinks 78 in their bottoms and that at the upper ends of the countersinks or recesses 78 are upwardly projecting deeper recesses 80.

I shall now describe the pins for entering the countersink recesses 78 and recesses 80 for accurately centering the pins and also the bushings by which the centering pins are guided in the floor. 115

Mounted in the floor 10 at the proper spots are bushings 82, each having at its upper end a laterally, extending peripheral flange 84, provided with holes 86 to receive a spanner wrench. 120

The flanges 84 are countersunk in the floor 10, as shown in Figure 4.

The lower ends of the bushings 82 project 125 through the floor and are threaded as at 82^a to receive nuts 88. The nuts 88 may be pro-

vided with upwardly projecting points 90 adapted to be forced into the under surface of the floor 10, so that the nuts 88 will not rotate.

5 In some installations, as for instance, where the floor is originally built for use with a spotter of this kind, the nuts 88 may be secured to the floor by means of screws 92.

10 Slidably received in each bushing 82 is a centering pin 94, preferably provided at its lower end with a head 96 resting upon the movable frame of the pin spotter.

15 The relative locations of the bushings 82 are illustrated by dotted circles in Figure 1. They are so located that the centering pins 94 rest upon the frame members 26 and 27 except in one instance. The center ten pin is above the frame member 28 when the spotter is installed, and therefore the frame member 20 28 is provided at its central portion on its upper surface with a filler block 98, the upper surface of which is flush with the upper surfaces of the frame members 26 and 27 (Figure 3).

25 On the pins 94 between the heads 96 and the bushings 82 are suitable coil springs 100 for holding the pins 94 in their lowered position and for forcing them downwardly, if by any chance, any one of them should stick 30 when it has been raised.

35 It will be understood that the exact mode of installing my pin spotter will differ somewhat, depending upon whether the alley is built in contemplation of the use of such a spotter, or the spotter is installed in an alley installed at an earlier time and without the contemplation of the use of the spotter.

Operation.

40 I shall now briefly outline the steps in the operation of the spotter.

It will be understood that the bushings 82 have been installed in the floor at the proper points or spots, and that the spotter has been 45 installed in the manner hereinbefore described.

Normally the parts will stand in the position shown in Figure 3. The movable frame will be in its lowered position with the downwardly projecting flanges 27^a of the side frame members 27 resting upon the flanges 14^b of the fixed frame members 14 between the flanges 14^a and the ends of the frame members 12, 18 and 16.

55 The heads of the centering pins 94 will rest on the movable frame member and the upper ends of the centering pins 94 will be just below or substantially flush with the upper surface of the floor 10.

60 The lever 36 will be in its substantially horizontal position shown in Figure 3, and its rear end will hold the plunger 74 in its raised position.

Assume then that the pin setter is operated, 65 it will be observed that when the pin setter

moves downwardly to position for depositing the pins on the alley floor 10, the plunger actuating pin 60 carried by the pin setter will enter the bushing 66, engage the plunger 74, force it downwardly, and thus depress the rear end of the lever 36 for raising the movable frame member, and thus forcing the pins 94 upwardly into the recesses 78 and 80 for accurately centering upon the proper spots, any of the ten pins 76, which happen to have been improperly set.

As soon as the pin setter is raised carrying with it the plunger actuating pin 60, the weight of the movable frame member will return the pin spotter parts to their normal 80 positions.

It will be understood that the operation of the pin spotter is the same, when it is actuated by the pin boy, except that the lever 36 is operated by the pin boy instead of by the 85 mechanical pin setter.

It will be observed from the foregoing that I have provided a pin spotter of very simple, durable and inexpensive construction.

My pin spotter is such that it can be conveniently installed in any alley. The parts are so simple that they do not easily get out of order, and they are so installed that access to the pin spotter is easy for the purposes of repair or replacement.

Attention is called particularly to the ease with which the bushings 82 may be replaced if that should ever become necessary. A spanner wrench is applied to the flange 84 and the bushing is simply screwed out of the nut 88 and a new one screwed into place.

In rare instances, the pins may become bent or broken. A pin may be readily replaced without interfering with the installation of the main parts of the spotter, and the replacement of a pin may be accomplished easily and in a very short time in the following manner:

The bushing 82 is simply screwed out, whereupon the pin may be lifted vertically through the floor. The hole in the floor, which receives the bushing, is large enough to permit the passage of the head 96 of the pin. A new pin is dropped into position where it will rest upon the movable frame, and the bushing is then screwed back into place. This is an important feature of my present invention.

There are many advantages arising from the manner of mounting the centering pins in the floor independent of any direct connection with the movable pin spotter frame.

The ease with which the pins may be removed and repaired or replaced has been mentioned.

Another advantage arises from the fact that frames of the kind herein described, which do not have the pins fastened to them, can be much more easily assembled and installed under an old alley, than is the case.

with a spotter in which the centering pins are directly connected to the spotter frame.

Sometimes, I find that in alleys already installed, there is great difficulty in putting in spotters of the former types, because the cement floor is so close to the under surface of the alley floor. A pin spotter of the kind herein disclosed can be conveniently installed in such an environment.

10 Another advantage arising out of the supporting of the pins independently of the spotter frame is due to the fact that variation in the position of the spotter frame horizontally does not interfere with the operation 15 of the pins nor cause them to bind.

By using the lever 36 and the secondary levers 46, as herein described, I have been able to cut down the weight of the spotter very substantially.

20 It will be noted that cooperation between the pin setter and pin spotter is provided by means, such as will never be in the way of the balls and therefore will never mar the balls.

From what has been said, it will be understood that changes may be made in the details of the construction of my pin spotter and in the size, arrangement and materials of the parts, without departing from the real spirit and purpose of my invention, and it 30 is my intention to cover by the claims of the patent to be issued upon this application any modified forms of structure or use of mechanical equivalents, which may be reasonably included within the scope of such claims.

35 I claim as my invention:

1. In a pin spotter structure, the combination of a fixed frame substantially triangular in outline having on its upper surface at each side spaced guide members, a vertically movable frame having portions slidably received in said guides and having a flat upper surface for coacting with centering pins, and centering pins slidably mounted above said movable frame and yieldingly pressed against the 40 top of said frame but not otherwise connected therewith.

2. In a pin spotter structure, the combination of a fixed frame substantially triangular in outline, having on its upper surface at each side spaced guide members, a vertically movable frame having portions slidably received in said guides, and means for actuating said movable frame, comprising a lever pivoted between its ends on said fixed frame and having one end resting beneath the apex portion of the movable frame, secondary levers pivoted on said fixed frame in a plane substantially at right angles to that of the movement of the first lever, each having one end resting under a corner of the movable frame and another end standing in the path of the downward travel of the other end of said first lever.

3. In a pin spotter structure, the combination of a fixed frame substantially triangular

in outline, having on its upper surface at each side spaced guide members, a vertically movable frame having portions slidably received in said guides, and means for actuating said movable frame, comprising a lever pivoted between its ends in said fixed frame and having one end resting beneath the apex portion of the movable frame, secondary levers pivoted on said fixed frame in a plane substantially at right angles to that of the movement of the first lever, each having one end resting under a corner of the movable frame and another end adapted to be actuated by downward movement of the other end of said first lever.

4. In a pin spotter structure, a fixed supporting frame adapted to be installed underneath a bowling alley floor, a movable triangular frame above the fixed frame, said fixed frame having means for guiding the movable frame in vertical movement, and means for raising the movable frame from the fixed frame, comprising a lever pivoted between its ends on the fixed frame and having one end resting under one corner of the movable frame, a pair of secondary levers pivoted to said fixed frame, each having one end underneath a corner of the movable frame, the parts being so arranged that the downward movement of the other end of said first lever imparts downward movement to the other 90 ends of the said secondary levers.

5. In a pin spotter structure, the combination of a plurality of centering pins adapted to be slidably mounted in a bowling alley floor, a fixed frame, a vertically movable triangular frame arranged for cooperating with said pins, and means for raising said movable frame, said means including a lever pivoted to said fixed frame, and having an end projecting beyond said movable frame, a 100 slidably mounted plunger resting on said projecting end, a suitably mounted bushing receiving said plunger, and means adapted to be mounted on a pin setter for engaging said plunger, when such a setter is moved to a 110 certain position for operating on the plunger and actuating said lever.

6. In a pin spotter structure, the combination of a fixed frame substantially triangular in outline having on its upper surface at 115 each side spaced guide members, a vertically movable frame having portions slidably received in said guides, and centering pins slidably supported above said movable frame and adapted to be raised by the upward movement thereof.

7. In a pin spotter structure, the combination of an alley floor having a plurality of holes, with fastening elements secured to the floor at the lower ends of the holes, a plurality of headed bushings received in said holes, adapted to be inserted from above and to engage said elements for locking the bushings in place, and means for mounting pins for sliding adjustment in the bushings.

8. In a pin spotter structure, the combination of an alley floor having a plurality of holes with nuts secured to the under side of the floor in registry with the holes, headed 5 bushings in said holes, screwed into said nuts, and means for mounting pins for slidable adjustment in the bushings.
9. In a pin spotter structure, the combination of an alley floor having a plurality of 10 holes, with fastening elements secured to the floor at the lower ends of the holes, a plurality of bushings received in said holes, adapted to be inserted from above and to engage said elements for locking the bushings 15 in place, and means for mounting pins for slidable adjustment in the bushings.
10. In a pin spotter structure, the combination of an alley floor having a plurality of 20 holes, with nuts secured to the under side of the floor in registry with the holes, bushings in said holes screwed into said nuts and removable therefrom, a pin slidably received in each bushing having on its lower end a head of smaller diameter than the aperture in 25 its nut, and means for raising the pins.
11. In a pin spotter structure, the combination of a fixed frame, substantially triangular in outline, a vertically movable frame, and means for actuating said movable frame, comprising a lever pivoted between its ends on said fixed frame and having one end resting beneath the apex portion of the movable frame, secondary levers pivoted on said fixed frame in a plane substantially 30 at right angles to that of the movement of the first lever, each having one end resting under a corner of the movable frame and another end standing in the path of the downward travel of the other end of said first lever.
12. In a pin spotter structure, the combination of supporting means having spaced 35
- guide members with a vertically movable frame, means for actuating said movable frame, comprising a lever pivoted between its 45 ends on said supporting means and having one end resting beneath the apex portion of the movable frame, secondary levers pivoted on said supporting means in a plane substantially at right angles to that of the movement 50 of the first lever, each having one end resting under a corner of the movable frame, and another end standing in the path of the downward travel of the other end of said first lever. 55
13. In a pin spotter structure, the combination of fixed supporting means with a vertically movable frame, means for actuating said movable frame, comprising a lever pivoted between its ends on said fixed supporting means and having one end resting beneath the apex portion of the movable frame, secondary levers pivoted on said supporting means in a plane substantially at right angles to that of the movement of the 60 first lever, each having one end resting under a corner of the movable frame and another end standing in the path of the downward travel of the other end of said first lever. 65
14. In a pin spotter, the combination of a 70 plurality of centering pins adapted to be slidably mounted in a bowling alley floor, a pin spotter structure for raising said pins for spotting bowling pins, including a reciprocating actuating member having a projecting end, a slidably mounted plunger resting on said projecting end, a suitably mounted bushing receiving said plunger, and means adapted to be mounted on a pin setter for engaging said plunger, when such a setter is 75 moved to a certain position for operating on the plunger and actuating said member. 80

Des Moines, Iowa, August 22, 1927.

JACOB P. BUSCHER.
